T. W. McDILL.

Wheel-Cultivator.

No. 29.707.

Patented Aug. 21. 1860.

UNITED STATES PATENT OFFICE.

T. W. McDILL, OF OQUAWKA, ILLINOIS.

IMPROVEMENT IN CULTIVATORS.

Specification forming part of Letters Patent No. 29,707, dated August 21, 1860.

To all whom it may concern:

Be it known that I, T. W. McDILL, of Oquawka, in the county of Henderson and State of Illinois, have invented a new and Improved Cultivator; and I do hereby declare that the following is a full, clear, and exact description of the same, reference being had to the annexed drawings, making a part of this specification, in which—

Figure 1 is a side sectional view of my invention, taken in the line *x x*, Fig. 2; Fig. 2, a plan or top view of the same.

Similar letters of reference indicate corresponding parts in the two figures.

The object of this invention is to obtain a cultivator which may be readily manipulated, or which may be attended and guided with but little labor. This result is obtained in consequence of provision being made for controlling the implement with facility by giving some of its plows an independent adjusting-motion independently of the draft-motion, whereby the implement may be kept in its proper course and obstructions readily passed over, the implement, also, by a very simple adjustment, admitting of being readily drawn from place to place.

The invention consists in a novel arrangement of adjustable shares, substantially as hereinafter described, whereby the desired end is attained.

To enable those skilled in the art to fully understand and construct my invention, I will proceed to describe it.

A represents an axle, and *B B* wheels attached to the arms thereof. The central part of this axle is curved in bow form, as shown at *a*, in order that it may form no obstruction to the plants as the machine is drawn along.

To each end of the axle *A* there is attached a bar, *b*. These bars are parallel with each other, and are connected at their back ends by a cross-piece, *c*, which is also curved at its center in bow form, as shown at *d*, the bow *d* being in line with the bow *a* of the axle, the former being for the same purpose as the latter. The front ends of the bars *b* have each a goose-neck, *e*, attached to them by bolts *f*, which pass through oblong eyes *g* on the bars, and allow the goose-necks a certain degree of longitudinal play. The goose-necks *e e* are attached to

a bar, *h*, which has the draft-pole *B'* connected to it.

Through the axle *A*, at equal distances from each side of its center, there pass bolts *i i*, both of which are shown in Fig. 2. The back ends of these bolts are provided with heads, and the bolts pass through clevises *j j*, attached to the front ends of bars *k k*. (See more particularly Fig. 1.) This mode of attaching the bars *k k* to the axle *A* admits of the former having a lateral and turning movement. Each bar *b* has a handle, *l*, attached to it, and also an upright, *m*, the latter being connected by traverse-bars *n n*, which are perforated at their ends and secured by pins *o*, which pass through the uprights *m*. The back ends of the bars *k k* have each a pintle, *p*, attached, and said pintles pass through loops or guides *q q*, which are attached to the cross-piece *c*, said guides being sufficiently long to allow the bars *k k* a certain degree of lateral play or movement.

To each bar *b* a plow-standard or foot, *r*, is attached by a bolt, *s*, and the standards or feet are braced by rods *t*, which have jam-nuts *u u* on them—two on each—between which the standards or feet are placed. To the lower end of each foot or standard a plow, *v*, is attached. To each bar *k* there is also attached a similar standard or foot, *w*, the lower ends of which have plows *a'* secured to them. The standards or feet *w* are braced by rods *b'*, having jam-nuts *c'* on them.

From the above description it will be seen that as the implement is drawn along the bars *k k* and plows *a'* may be moved laterally, either to the right or left, and in case of the team moving either to the right or left, out of a proper course, the plows *a'* may be kept in a direct line until the team is brought back to the proper place. In case, also, of the plows striking obstructions which may be in their path, they will be readily deflected or turned so as to pass over or by the obstruction. This arrangement of the bars *k k* renders the manipulation of the implement very easy, greatly reducing the labor attending the use of the cultivator.

When necessary—as, for instance, in furrowing—the bars *k k* may be detached and the plows *v* only used. The depth of the plows *v*,

as also that of the plows a' , may be regulated by adjusting the nuts u e' .

When the machine is to be moved from place to place the bars b b k k are turned bodily upward, and the whole framing made to rest on the draft-pole, the play of the bolts f in the eyes g readily admitting of such movement.

I do not claim the curved or bow-shaped axle A and cross-piece c , for they have been previously used; but

I do claim as new and desire to secure by Letters Patent—

The arrangement of the axle A and bars b b k k and cross-piece c with the loose connection of the draft-pole B' to the machine, substantially as and for the purposes set forth.

T. W. McDILL.
